UNITED STATES PATENT OFFICE.

JAMES B. HOGE AND CHARLES W. WARD, OF CLEVELAND, OHIO.

DESIGN FOR AN AUTOMOBILE SIGNAL-CASING.

47,668.

Specification for Design.

Patented Aug. 3, 1915.

Application filed April 10, 1915. Serial No. 20,586. Term of patent 14 years.

To all whom it may concern:

Be it known that we, JAMES B. HOGE and CHARLES W. WARD, both citizens of United States, residing at Cleveland, in the county of Cuyahoga and State of Ohio, have invented a new, original, and ornamental Design for Automobile Signal-Casings, of which the following is a specification, reference being had to the accompanying drawing, forming part thereof.

Figures 1, 2 and 3 are respectively front,

side and rear views of an automobile signal casing, showing our new design.

We claim:

The ornamental design for an automobile signal casing, as shown.

JAMES B. HOGE.
CHARLES W. WARD.

Witnesses:

F. E. WRIGHT,
N. G. CREN.
